J. A. POWER.
EVAPORATING APPARATUS.
APPLICATION FILED JAN. 27, 1912.

1,028,777.

Patented June 4, 1912.

UNITED STATES PATENT OFFICE.

JOHN ANTHONY POWER, OF BABYLON, NEW YORK.

EVAPORATING APPARATUS.

1,028,777.

Specification of Letters Patent.

Patented June 4, 1912.

Application filed January 27, 1912. Serial No. 673,782.

To all whom it may concern:

Be it known that I, JOHN A. POWER, a citizen of the United States, and a resident of Babylon, in the county of Suffolk and State of New York, have invented a new and Improved Evaporating Apparatus, of which the following is a full, clear, and exact description.

The object of the invention is to provide a new and improved evaporating apparatus, more especially designed for evaporating salt or other water with a view of obtaining a supply of fresh water, and arranged to permit of conveniently rotating the steam heating device within the shell, to permit convenient access to the parts thereof, to make repairs quickly, and to prevent leakage.

For the purpose mentioned use is made of a shell provided with fixed steam inlet and outlet pipes, and a heating device mounted to turn on the inner terminals of the said fixed inlet and outlet pipes.

A practical embodiment of the invention is represented in the accompanying drawings forming a part of this specification, in which similar characters of reference indicate corresponding parts in both views.

Figure 1 is a side elevation of the evaporating apparatus, the parts being shown in section; and Fig. 2 is an enlarged sectional side elevation of one of the connections between the heating device and the corresponding inlet or outlet pipe.

The shell A of the evaporating apparatus is provided at its lower end with a valve inlet B for filling the shell A with water to a predetermined level, and the upper end of the shell A is provided with an outlet C for conducting the vapors to a suitable condenser for condensing the vapor, with a view to furnish a fresh water supply. The water in the shell A is heated by a heating apparatus D mounted to turn to permit of conveniently cleaning or repairing the same whenever it is desired to do so, access being had to the device through a door E arranged on the shell A, as indicated in Fig. 1. The heating device D is mounted

to turn on the steam inlet pipe F and the outlet pipe G, both pipes F and G being provided with flanges F' and G' for conveniently securing the pipes F and G in position on the shell A, the outer end of the pipe F being connected with a suitable steam supply, and the outer end of the pipe G be-

ing connected with a suitable place of discharge for the steam and the water of condensation. The inner ends F² and G² of the pipes F and G are bent toward each other and are in axial alinement with each other in the vertical center of the shell A, as plainly indicated in Fig. 1, so as to form pivots for the heating device D to turn on, and at the same time provide connections for the passage of the steam from the pipe F to and through the heating device D and to the outlet pipe G.

The heating device D consists essentially of oppositely-disposed manifolds H and H' connected with each other by coils I so that steam can pass from the pipe F into the manifold H, coils I, manifold H' and finally into the pipe G. The steam during its passage through the coils I heats the same and consequently the water contained in the shell A to properly evaporate the said water for the purpose previously mentioned. The pivotal connections between the manifolds H and H' with the ends F² and G² of the pipes F and G are alike so that it suffices to describe but one in detail, special reference being had to Fig. 2. The middle portions of the manifolds H and H' are provided with seats H² in vertical alinement with each other and engaged by conical terminals J connected by nipples K with the corresponding ends F² and G², and the said terminals J are provided with flanges J' engaged by a coupling L screwing on the exteriorly-threaded seats H² of the manifolds H and H'. Thus by the arrangement described a ground joint is provided between the manifolds H and H' and the angular ends F² and G² of the fixed pipes F and G to permit of conveniently turning the heating device D within the shell A.

The coils I have ground joint connections with the manifolds H and H', and the said ground joint connections are similar to the ones above described in reference to the connections between the manifolds H, H' and the pipes F and G, that is, each manifold H, H' is provided with reduced seats H³ engaged by the conical terminals N of the coils I. The said conical terminals N are provided with flanges N' engaged by couplings O screwing on the seats H³.

By the arrangement described the coils I can be readily fastened in position on the manifolds H and H', and in case any one of the coils is worn out it can be readily

replaced by a new one without disturbing the position of the remaining coils. It will also be noticed that by having the ground joint connections between the manifolds H, 5 H', the pipes F, G and the coils I as described, leakage is reduced to a minimum.

The shell A is provided with the usual gage P for observing the level of the water in the shell A, the water level being normally 10 at the lower half portion of the coils I while the upper half portion of the coils acts as a superheater. The upper end of the shell is provided with a gage Q and a safety valve R, and the lower portion of the shell A 15 is provided with a water draw-off cock or a faucet S and a valve drain T for draining the shell A of water whenever it is desired to do so.

Having thus described my invention, I 20 claim as new and desire to secure by Letters Patent:

1. An evaporating apparatus, comprising a shell having a door, a water inlet, a vapor outlet, steam inlet and outlet pipes arranged 25 within the shell and fixed thereto, and a heating device mounted to turn on the inner ends of the said fixed steam inlet and outlet pipes and connected therewith for the circulation of steam through the said heating device.

2. An evaporating apparatus, comprising a shell, a pair of oppositely-disposed manifolds within the said shell, coils connecting the said manifolds with each other, inlet and 35 outlet pipes fixed in the said shell, and

ground joints in axial alignment and connecting the said manifolds with the said fixed pipes.

3. An evaporating apparatus, comprising a shell, oppositely-disposed manifolds within the said shell and provided at their middle with seats, coils connecting the said manifolds with each other, inlet and outlet pipes fixed in the said shell and having conical terminals engaging the said seats, and 40 coupling members for fastening the said terminals in position on the seats.

4. An evaporating apparatus, comprising a shell, oppositely-disposed manifolds within the said shell and provided at their 45 middle with aligned inlet and outlet seats and with reduced coil seats, coils intermediate the said manifolds and having conical terminals engaging the said reduced coil seats, coupling members for fastening the said terminals in position on the said coil seats, inlet and outlet pipes fixed in the said shell and having conical terminals engaging the said inlet and outlet seats, and coupling members for fastening the said terminals of 50 the inlet and outlet pipes in position on the said inlet and outlet seats.

In testimony whereof I have signed my name to this specification in the presence of two subscribing witnesses.

JOHN ANTHONY POWER.
